BY J. P. Drake

ATTORNEY.

UNITED STATES PATENT OFFICE.

CHARLES A. MANN, OF BUFFALO, NEW YORK.

FENCE-POST.

SPECIFICATION forming part of Letters Patent No. 254,350, dated February 28, 1882.

Application filed January 17, 1881. Renewed December 10, 1881. (No model.)

To all whom it may concern:

Be it known that I, CHARLES A. MANN, of Buffalo, in the county of Erie and State of New York, a citizen of the United States, have made certain Improvements in Fence-Posts, &c., for Barbed Fence-Wire, of which the following is a specification.

This invention relates to a single iron post and its attached anchors.

10 The invention will be understood as set forth in the following specification and claims.

In the drawings, Figure 1 is a side elevation, showing the post and anchor-base as it sets in the ground, also the clip holding the wire. 15 Fig. 2 is a front elevation of same; Fig. 3, a perspective of the clip, full size.

A represents the single piece of iron, of any suitable size and shape, which is bent at *a* at right angles a short distance, and at sufficient 20 space from the top to give proper height to said post above the ground, and is again bent down at right angles, at *b*, making the penetrating part of the post A', and leaving a step or shoulder forming a base, *c*, that rests on the 25 ground, and which gives additional support to the whole.

B is an anchor-base, made or cast usually in one piece, consisting of a flat part that penetrates the earth, with or without flanges on top, 30 at *d*, and with wings or flanges *e e* next to the penetrating part of the post A', which runs through loops *f f* on the flanges, preventing any side movement of either post or anchor. The top of the anchor is provided with an upright piece, *g*, which is riveted to the post A just above the ground. From this projects a 35 bent lug or loop, *h*, holding the end of a brace, C, whose other end stands in the ground at a slant, aiding in preventing any side movement, 40 while the wings or flanges *e e* on the anchor-base B prevent any forward or back swaying or any divergence by any direct pull or pressure. The part *g* and base-anchor generally also aid greatly in strengthening the post A.

where it is driven into the ground. An additional brace, D, is attached by a single rivet or pin to the front or back of the post A, as shown at *i*, Fig. 2, and which has usually an anchor of some sort fastened to its outer end, and which sets in the ground. This is mainly 45 what is called a "straining-brace," when the wire is strung either way, and the brace is 50 swung round to either side desired by the pin or single rivet *i*.

E represents the clip or wire-holder, which 55 is especially constructed to fit this post A, having an opening, *k*, to fit over the post A, leaving a side piece or space, *l*, between the opening *k* and curved back *m* to set the wire *p* therein. This hole *k* is a little larger than 60 the post A, so as to set on easily, and when the barbed fence-wire is put in between the post and back *m* (which has teeth) a wedge or nail, *s*, (see Figs. 1 and 2,) is driven in the opening *k*, between the post and outer edge, 65 *l*, of the clip. This throws the curved back *m* over the wire and jams it against the post, and thus holds it immovably between.

The whole device is simple, durable, and 70 easily made.

I claim—

1. In combination with the iron post A A', the anchor-base B, riveted to the post, and having the flanges *e e*, the brace loop or lug *h*, and brace C, all substantially as and for the 75 purpose specified.

2. In a fence-post, the combination of the upright post A A' *b* with an anchor, B, having the upright attaching portions *g e* and an intervening ledge closely fitting into the post, 80 as set forth.

In witness whereof I have hereunto signed my name in the presence of two subscribing witnesses.

CHAS. A. MANN.
